FREE-PISTON INTERNAL-COMBUSTION
ENGINE

Hans Steiner, Winterthur, Switzerland, assignor
to Sulzer Freres, Societe Anonyme, Winterthur,
Switzerland

Application May 9, 1945, Serial No. 592,745
In Switzerland May 12, 1944

9 Claims. (CL. 123—46)

1

The invention relates to a free-piston internal combustion engine and has the purpose of enabling the frequency of the stroke to be varied, and in particular to be increased.

For free-piston internal combustion engines it is known to employ an energy storage cylinder or buffer for regulating the length and frequency of the stroke of the free pistons, at each stroke a gas, for instance air, being compressed and again expanding when the free pistons have reached the outer dead centre. The energy collected in the buffer cylinder by compression serves to equalise the rest of the energy acting upon the free piston in the opposite direction. In stationary service the quantity of energy acting upon the free piston in one stroke must be equal to that acting in the other stroke, as otherwise the length of the stroke would be continuously increased or decreased.

In the present invention it is now proposed that at least one free piston should have two or more energy storage cylinders which absorb energy in different strokes, energy being generated by the rise of pressure at least in the latter part of the stroke.

Three embodiments of the invention are shown diagrammatically in the drawings.

Fig. 1 shows the diagrams of the quantities of energy acting on the power piston, the compressor piston and the buffer piston.

Fig. 2 shows the distribution of the accelerating and retarding work done on the free piston.

Figs. 3-8 show three different types of buffer cylinder and the appertaining diagrams.

Figs. 9 and 10 show the two energy storage cylinders of a free piston with the appertaining diagram.

Fig. 11 shows an embodiment in which one end of a compressor cylinder serves as an energy storage cylinder.

Fig. 12 shows a further execution with a common regulating device for the buffer cylinders of the two free-pistons.

In Fig. 1 the forces acting on the mass of the free-piston in a free-piston engine are set off on the ordinates with the stroke as abscissa, the upper section showing the total force of the power piston, the middle section that of the compressor piston and the lower section that of a buffer piston which absorbs energy during the outward stroke. Accordingly the area *a* represents the expansion work of the power piston and the area *b* the compression work of the compressor piston.

For steady service of the engine, if the friction of the pistons and of the linkage, the work for the injection of fuel, etc., be disregarded, it is thus necessary for the area *a* to be equal to the area *b*.

2

The work done in compressing the combustion air in the combustion cylinder is represented by the area *c*. This must again be equal to the sum of the work done in the return stroke of the compressor, i. e., the area *d* and the work temporarily stored in the buffer cylinder, i. e. the area *e*.

When one buffer cylinder only is employed, the energy acting from the combustion cylinder outwards, i. e., from inside upon the free-piston masses, is represented by the areas *a* and *c*. The energy acting from the outside comprises the areas *b*, *d* and *e*.

The speed of a free-piston engine in strokes per unit time depends on the one hand on the magnitude of these energies, and on the other hand on their distribution over the stroke. This latter process is illustrated in Fig. 2, in which equal accelerating and retarding energies are circumscribed by the curves *f* and *g*. Nevertheless, different speeds are obtained owing to the differing distribution of the accelerating energy, which can be secured for instance by altering the method of operation of the buffer cylinder. On the other hand, whenever any modification is made to the buffer energy, the length of the stroke is also influenced, as an equilibrium represented by the equality of the areas

$$a+c=b+d+e$$

must always prevail.

In Fig. 3 is shown a buffer cylinder 1, whose piston 2 is coupled to or forms part of a free piston. In steady service the piston 2 has a stroke *h* between the inner and outer end positions *H₁* and *H₂* marked in chain-dotted lines. Air under pressure, for instance, is supplied to the buffer cylinder 1 from the pipe 3. In accordance with the tension of the spring 5, which can be altered continuously by the spindle 6 within the required limits, the pressure of the air at supply is reduced to a definite normal value by means of the regulating valve 4.

The piston 2 is loaded by this normal pressure from the inner dead centre *H₁* until it reaches the feed inlet 7, while in the last part of the stroke, when the port 7 has been covered, energy is stored in the cylinder 1 by compression of the air in it. The forces arising from the course of the air pressure are represented in Fig. 4. By means of the spindle 6 an initial force *P₁* can be set in the buffer cylinder, from which develops the final force *P₂* at the outer dead centre. With an initial force *P₂*, on the other hand, the final force rises, provided the stroke is the same, to 55 the value *P₄*.

Now while in the buffer cylinder shown in Fig. 3 the initial pressure of the energy accumulation can be regulated, in Fig. 5 the beginning of com-

pression or of energy accumulation is altered. Instead of the single feed inlet 7, there are three of these provided in the buffer cylinder 8 with the piston 2, namely, the inlets 10, 11 and 12, which can be shut off from or connected to the space 15 by adjusting the valve 13 by means of the handwheel 14. The space 15 can again be fed with air at a constant pressure P_1 or may be in communication with the outer air. In the latter case the feed pressure of the buffer cylinder 8 in Fig. 5 would correspond to the pressure of the atmosphere.

It can be seen from Fig. 6 that compression begins at H_{10} , or only at H_{11} , or finally at H_{12} , according to the position of the valve 13. Accordingly different final forces P_{10} , P_{11} and P_{12} result in the buffer cylinder 8. If all three ports are open, the smallest quantity of energy is accumulated, and the greatest quantity of energy if only port 10 is open.

The energy accumulating capacity of the buffer cylinder can further be changed by altering the storage volume, i. e., the volume at the outer dead centre of the piston 2. In Fig. 7 there is provided in the buffer cylinder 16 an hermetically sealing piston 17 which can be displaced by means of the spindle 18. As in Fig. 3 the buffer cylinder 16 has only one port 7, through which for instance air is supplied at atmospheric pressure or at some higher pressure.

Fig. 8 gives the corresponding diagram. The initial force P_1 is always the same and the beginning of the pressure increase always lies at H_7 . On the other hand, in the position of the piston 17 shown a final force P_{17} is reached, while by moving the piston 17 to the right the final pressure of the pressure increase and thus the final force can be reduced continuously down to the value P_{19} , when the end-position 19 is reached.

One free piston may have two or more buffer cylinders whose absorption of energy takes place in different strokes. In this case all the buffer cylinders may be of similar design, or buffer cylinders differing among themselves may be combined with the free piston.

In Fig. 9 a buffer cylinder 20 absorbing energy in the outward stroke and a cylinder 21 absorbing energy in the inward stroke are provided. The two cylinders are connected through a common pressure regulating valve 4 to a pressure pipe 3. On the other hand the feed openings 22 and 23 are at different distances from the outer dead centre H_a and from the inner dead centre H_i . In Fig. 10 the course of the forces is shown for differing initial pressures. The fact that the left-hand piston surface of piston 2 is smaller than the right-hand surface has the result that the initial force P_{20} in the cylinder 20 is higher than the initial force P_{21} in the cylinder 21. The same is also true at a higher initial pressure, the forces P_{20} and P_{21} , for instance, presenting themselves.

By the use of at least two buffer cylinders with energy absorption in different strokes, therefore, a much more pronounced displacement of the common centre point of the working areas of the buffer cylinders, i. e., a very effective change in the distribution of the work along the stroke, is obtained. Thus for instance the working surface k acting outwards may be enlarged, remain constant, or be reduced when the two buffer cylinders are given corresponding dimensions, while at the same time the work k acting inwards is increased by the alteration of the feed pressure. This measure allows of a very simple

and accurate regulation of the stroke frequency.

In Fig. 11 the power pistons 25 and 25a work in the combustion cylinder 26, the compressor pistons 27 and 27a in the compressor cylinders 28 and 28a, and the buffer piston 29 in the buffer cylinder 30. The free-piston 25a, 27a, which works without a buffer cylinder, is connected to the free-piston 25, 27 through the coupling linkage 75.

10 The compressor piston 27 draws in scavenging and combustion air on the right-hand side through the suction branch 31 and compresses it, to deliver it through the pipe 32 with a certain excess, and through the inlet port 34 into the combustion cylinder 26. The compressor piston 15 27a draws air or gas through the suction pipe 31a and delivers it through the delivery valves into the delivery pipe 76, which is connected to a consumption main for air or gas.

15 The fuel pump 55, whose plunger performs a compression stroke through the cam 78 in the inner dead center of the free-pistons, delivers fuel through the injection valve 79 into the combustion cylinder 26. The injection is adjusted 20 by linkage 77. At the end of the expansion stroke 25 of the free-pistons the exhaust ports 59 open and the combustion gases are led off by the pipe 60. The energy of the combustion gases can be utilized in the turbine (not shown in the drawing) 25 which drives, for instance, auxiliary equipment such as lubricating oil pumps, cooling-water pumps and the like, or a precompressor for the compressor 28 or for the compressor 28a. A buffer cylinder and a buffer piston (not shown in 30 Fig. 11) may be provided on the compressor 28a, formed like the buffer cylinder 30 and buffer piston 29 on the compressor 28, so that each free-piston is connected to one buffer cylinder only, the free-pistons 25a, 27a being connected to one 35 that absorbs energy during the outward stroke and the free-piston 25a, 27a to one that absorbs energy during the inward stroke.

40 The air excess depends on whether the free-piston engine works only as a power gas producer 45 or whether compressed air is supplied through one of the pipes branching off from the pipe 32 to other consumers. This determines the size of the compressor cylinder 28.

45 The left-hand side of the compressor cylinder 50 28 draws in air from the pipe 35 and compresses it. The compressed air is supplied through ports 36 into the pipe 37 and, in the position of the 55 change-over member 38 shown, through the pipe 39 and the inlet port 40 also to the combustion cylinder 26. A larger or smaller number of the ports 36 are closed according to the position of the piston 41, which can be altered by means of the handwheel 42 and the worm gear 43. Consequently the delivery of compressed air into the 60 pipe 37 stops as soon as the piston 27 has covered the last open port 36 during the inward stroke. From this point on the lefthand side of the compressor 28 works as a buffer cylinder with pressure increase during the inward stroke.

65 If the change-over member 38 is moved from the position I into the position II, the left-hand side of the compressor 28 works exclusively as a buffer-cylinder in the sense of Figs. 5 and 6. The pipe 44 can then be in communication with the 70 outside air or may supply a gas under pressure.

75 The buffer cylinder 30 with energy absorption in the outward stroke is fed through the pipe 45 at a pressure which is kept constant and regulated by the pressure regulating device 46. The supply 47 and discharge 48 of compressed air are

shut off from the pipe 45 by means of the valves 49 and 50. The valve rod 51 is provided with stops for opening the valves 49 and 50 and is loaded on the one hand by the spring 52 and on the other by the pressure in the membrane 53 which is in communication with the pipe 45. The tension of the spring 52 is set simultaneously with the displacement of the piston 41 by means of the handwheel 42. If it is increased, the force of the spring 52 is strong enough to open the valve 49 until, owing to the entry of compressed air from the pipe 47 to the pipe 45, the loading of the valve spindle 51 by the membrane 53 balances the loading of the spring 52. Otherwise the buffer cylinder 30 works in the same way as the buffer cylinder 1 in Figs. 3 and 4.

In Fig. 12 the free-piston engine has two free-pistons 25, 27, 29 which work with the combustion cylinders 26, the compressor cylinders 28 and the buffer cylinders 30 and 54. The stroke of the two free-pistons 25, 27 and 29 can be synchronised by a coupling linkage not shown in detail in the drawing but indicated by dash-dotted lines at 75, Fig. 11. The fuel pump 55 injects fuel through the fuel valve 56 in the neighbourhood of the inner dead centre of the free pistons. The necessary combustion and scavenging air is supplied by the single-acting compressor cylinders 28 through the pipe 57 to the inlet ports 58. As the free-piston engine works as a power gas generator, the power gas emerges through the outlet ports 59 under pressure into the pipe 60 which leads to a power gas consumer not shown in the drawing, for instance to a turbine which drives a generator, a ship's propeller or a machine doing work.

The two buffer cylinders 30 are fed through the pipe 61, the two buffer cylinders 54 through the pipe 62 from the container 63 as in Figs. 3 and 4. The feed pressure is regulated by means of the pressure regulating devices 64 and 65 whose design and method of working correspond to the regulating device 46 described for Fig. 11.

The normal pressure for feeding the buffer cylinders 30 and 54 is adjusted by the lever 66 which at the same time sets the quantity of fuel to be injected by the fuel pump 55. By means of the lever 66, the rod 67 and thus the cams 68 and 69 can be displaced, so that the loading of the springs 70 and 71 can be adjusted according to the profile of the cams 68, 69. By a special design of the paths of the cams 68 and 69 the change in the feed pressure of the buffer cylinders 30 and 54 can be brought into a quite definite proportion to the change in the fuel quantity to be injected. Moreover, these cam paths can also differ, so that the feed pressure for the cylinders 30 is changed in a different way from the feed pressure for the cylinders 54.

In order to be able to cut out the buffer cylinders 54 when starting up, relief valves 72 are provided. By opening these valves an increase of pressure in the cylinders 54 is prevented. It is then preferable for the connection through the pipe 62 to the tank 63 to be interrupted by closing the valve 73.

According to the invention it is now possible, even with two free pistons working in opposite directions, for one of the free pistons to be provided with two energy storage cylinders or buffers which absorb energy in different strokes. It is also possible, however, for one of the free pistons to be provided with a buffer cylinder which absorbs energy in one stroke, for instance in the outward stroke, and for the other free piston to

be provided with a second buffer cylinder whose absorption of energy takes place in the opposite stroke, that is in the inward stroke. Finally, each free piston may be provided with two or more buffer cylinders.

I claim:

1. Free-piston internal combustion engine which comprises at least two free pistons having at least two energy storage or buffer cylinders which absorb energy in different strokes, it being possible to accumulate energy by pressure increase at least in the latter part of the stroke, in order to enable the frequency of the stroke to be altered, and in particular to be increased, and a port for feeding the cylinder with gas.
- 10 2. Free-piston internal combustion engine as claimed in claim 1, which comprises a compressor cylinder having one end constructed as a buffer cylinder.
- 20 3. Free-piston internal combustion engine as claimed in claim 1, characterised in that the piston of a buffer cylinder is constructed to control one or more ports for feeding the cylinder with gas, preferably under pressure.
- 25 4. Free-piston internal combustion engine as claimed in claim 1, which comprises a regulating device for the feed pressure of a buffer cylinder.
- 30 5. Free-piston internal combustion engine as claimed in claim 1, which comprises a device for adjusting the beginning of the pressure increase in the buffer cylinder.
- 35 6. Free-piston internal combustion engine as claimed in claim 1, which comprises a device for changing the volume of the buffer cylinder.
- 40 7. Free-piston internal combustion engine as claimed in claim 1, which comprises a device regulating the feed pressure and a device for setting the beginning of pressure increase are arranged at the end of a compressor cylinder next to the combustion cylinder, in order to make possible a pressure supply during service in the first part of the stroke and in the second part the storage of energy and also, during starting, service without compression.
- 45 8. Free-piston internal combustion engine as claimed in claim 1, which comprises one or more buffer cylinders provided with a relief valve in order to enable them to be put out of action, for instance during starting.
- 50 9. Free-piston internal combustion engine as claimed in claim 1, which comprises a member for regulating the power of the buffer cylinders so coupled to the member regulating the power of the engine that they can be adjusted together.
